DESIGN FOR A BATHING SUIT.

Application filed December 11, 1928. Serial No. 29,217. Term of patent 3½ years.

To all whom it may concern:

Be it known that I, DOROTHY LONG, a citizen of the United States, and a resident of the city of New York, in the county of New York and State of New York, have invented the new, original, and ornamental Design for Bathing Suit, of which the following is a specification.

The dominant feature of the design resides in the sunburst effect at the front and the rear of the dress produced by tucks radiating from one side and extending to the opposite side.

Reference is had to the accompanying drawing, forming part thereof, wherein

Figure 1 is a three-fourths front perspective view of a bathing suit showing my new design, the same being illustrated on a figure indicated by dotted lines;

Figure 2 is a rear perspective view of the bathing suit shown in Figure 1, the same being illustrated on a figure indicated by dotted lines.

I claim:

The ornamental design for a bathing suit substantially as shown and described.

Signed at New York, in the county of New York and State of New York this 7th day of December, A. D. 1928.

DOROTHY LONG.
